(57) **CLAIM**

The ornamental design for a tail light signature, as shown and described.

DESCRIPTION

FIG. 1 is a front left elevated perspective view of a tail light signature, showing our new design.

FIG. 2 is a front left perspective view thereof.

FIG. 3 is a front view thereof.

FIG. 4 is a left side view thereof.

FIG. 5 is another front view of the tail light signature shown on a vehicle; the vehicle is shown de-emphasized and in half-tone so as to illustrate environmental structure, which forms no part of the claimed design; and, FIG. 6 is another front view of the tail light signature with a mirror-image embodiment shown on the opposite side of a vehicle; the vehicle is shown de-emphasized and in half-tone so as to illustrate environmental structure, which forms no part of the claimed design.

The claimed design is shown within the broken lines. The broken lines illustrate a boundary of the design. The de-emphasized and half-tone portions shown outside the broken lines form no part of the claimed design, but are included to show environmental aspects thereof.
